FOREIGN PATENT DOCUMENTS

510300A2 1/1992 European Pat. Off. .

Primary Examiner—Marcus A. Jackson
Attorney, Agent, or Firm—Robert W. Welsh; S. Allan Fraser

[57] CLAIM

The ornamental design for a rechargeable flashlight, as shown and described.

DESCRIPTION

FIG. 1 is a perspective view of one embodiment a rechargeable flashlight;

FIG. 2 is a plan view of a rechargeable flashlight shown in FIG. 1;

FIG. 3 is a side view of a rechargeable flashlight shown in FIG. 1, the opposite side being a mirror image thereof;

FIG. 4 is a bottom plan view of a rechargeable flashlight shown in FIG. 2;

FIG. 5 is an end view of a rechargeable flashlight; and,

FIG. 6 is an end view of a rechargeable flashlight opposite that shown in FIG. 5.
